United States Patent Office

Des. 214,617
Patented July 8, 1969

214,617

PAINT CAN LID

Thomas V. O'Leary, 1722 Martins Lane,
Gladwyne, Pa. 19035

Original design application Mar. 16, 1967, Ser. No. 6,252,
now Patent No. 212,185, dated Sept. 10, 1968. Divided
and this application May 16, 1968, Ser. No. 12,532

Term of patent 14 years

Int. Cl. D9—02, 07

U.S. Cl. D9—264

Fig. 1

Fig. 2

Fig. 3

Fig. 4

FIG. 1 is a perspective view of a paint can lid embodying my new design;

FIG. 2 is an enlarged plan view;

FIG. 3 is an edge view thereof; and

FIG. 4 is a sectional view taken on line IV—IV of FIG. 2 on a further enlarged scale.

The broken line showing of a paint can in FIG. 1 is for illustrative purposes only.

This application is a division of design application Ser. No. D. 6252 filed Mar. 16, 1967, now Patent No. D. 212,185 granted Sept. 10, 1968.

I claim:

The ornamental design for a paint can lid, as shown and described.
